UNITED STATES PATENT OFFICE.

WILLIAM H. BRAUN, OF CINCINNATI, OHIO, ASSIGNOR TO FALLIS INC., OF CINCINNATI, OHIO, A CORPORATION OF OHIO.

DESIGN FOR A BOTTLE.

Application filed September 19, 1925. Serial No. 14,823. Term of patent 7 years.

To all whom it may concern:

Be it known that I, WILLIAM H. BRAUN, a citizen of the United States, residing at Cincinnati, in the county of Hamilton and State of Ohio, have invented a new, original, and ornamental Design for Bottles, of which the following is a specification, reference being had to the accompanying drawings, forming part thereof.

In the drawings,

I claim:

The ornamental design for a bottle, as shown.

WILLIAM H. BRAUN.
